Primary Examiner — Kimberly Barnes

(74) *Attorney, Agent, or Firm* — Morgan, Lewis & Bockius LLP

(57) **CLAIM**

The ornamental design for a docking station for cleaning robot, as shown and described.

DESCRIPTION

Docking station for cleaning robot

Reproduction **1.1** is a front view of a first embodiment of docking station for cleaning robot, showing our new design; Reproduction **1.2** is a back view thereof;

Reproduction **1.3** is a left view thereof;

Reproduction **1.4** is a right view thereof;

Reproduction **1.5** is a top view thereof;

Reproduction **1.6** is a bottom view thereof;

Reproduction **1.7** is a front perspective view thereof;

Reproduction **1.8** is a back perspective view thereof;

Reproduction **2.1** is a front view of a second embodiment of docking station for cleaning robot, showing our new design;

Reproduction **2.2** is a back view thereof;

Reproduction **2.3** is a left view thereof;

Reproduction **2.4** is a right view thereof;

Reproduction **2.5** is a top view thereof;

Reproduction **2.6** is a bottom view thereof;

Reproduction **2.7** is a front perspective view thereof; and

Reproduction **2.8** is a back perspective view thereof.

1 Claim, 16 Drawing Sheets
